UNITED STATES PATENT OFFICE.

LOUIS BLACK, OF NEW YORK, N. Y., ASSIGNOR OF ONE-HALF TO EASTMAN MACHINE COMPANY, OF BUFFALO, NEW YORK.

PRESSING AND STARCHING IMPLEMENT.

Application filed May 25, 1923. Serial No. 641,402.

To all whom it may concern:

Be it known that I, LOUIS BLACK, a citizen of the United States, residing at New York, in the county of New York and State 5 of New York, have invented a new and useful Improvement in Pressing and Starching Implements, of which the following is a specification.

This invention relates to pressing irons or 10 implements of that kind which are constructed so as to discharge a fluid, such as steam, against the goods for dampening the same while they are being pressed by means of the iron or implement, and more particularly to improvements in or attachments 15 for such pressing irons or implements whereby they are adapted to apply starch to the goods being pressed. Pressing irons or implements have been made heretofore, 20 in which the pressing face of the implement is provided with small perforations through which steam supplied to or generated in the implement is adapted to discharge against the goods while they are being pressed, such 25 pressing implements ordinarily being provided with a suitable valve or controlling device whereby the discharge of the steam for dampening the goods can be controlled at will.

30 One object of my invention is to provide a practical and efficient pressing iron or implement of this character equipped with a starching attachment or means, so arranged or combined with the implement that the 35 steam or fluid which is discharged from the implement for dampening the goods is impregnated with starch, or carries starch with it to the goods for starching the same simultaneously with the dampening and pressing 40 operation. Another object of the invention is to provide a starching attachment for the purpose stated, which is of inexpensive and desirable construction, such that the starch can be readily placed in the attachment and 45 renewed from time to time, as may be necessary, and such as to insure the proper delivery of the starch with the moistening fluid to the goods being pressed, and prevent clogging of the starch container or the 50 passages through which the starch passes to the goods.

In the accompanying drawings:

Fig. 1 is an elevation partly in section,

showing a pressing iron and starching attachment embodying my invention. 55

Fig. 2 is an enlarged sectional elevation of the starch container.

Fig. 3 is a horizontal section of the container on line 3—3, Fig. 2.

A represents the pressing iron or implement which, as illustrated in the drawings, is a hand iron adapted to be moved by hand over the goods to press them in the well known manner of using pressing irons. It will be understood, however, that the iron 60 illustrated is selected only for the purpose of showing the application and use of the starching attachment, and that the pressing iron or implement may be of other suitable construction or kind, whether in the nature 65 of a portable iron or of a fixed pressing implement or machine. B B' represent a supply pipe or hose connected with the pressing implement A for supplying thereto steam or other fluid suitable for dampening the goods, 70 the iron or implement A being provided in its bottom or pressing face with small discharge perforations *a* through which the steam or moistening fluid can be discharged 75 against the goods while they are being 80 pressed. It is common in pressing implements of this sort to provide the same with a valve or device whereby the discharge of the moistening fluid to the goods can be controlled or stopped and started at will, and 85 such a controlling valve or device is indicated at C. The implement illustrated is 90 heated by the usual gas burner or other heating element which also serves to superheat the steam for dampening the goods, and D indicates the fuel supply tube or connection for the heating element, not shown.

10 represents a starch container or receptacle through which the steam or moistening fluid passes on its way to the discharge 95 perforations *a* of the implement. As shown, this container is interposed in the supply pipe B B', through which the steam or moistening fluid is supplied to the implement. Starch is placed in this container or receptacle so that the steam or fluid in passing through the same becomes impregnated 100 with the starch, or carries starch in solution with it to the pressing implement. The starch container 10 preferably comprises a 105 receptacle provided with a removable cap

or cover 11, which as shown, is screw-threaded and is adapted to be screwed into an internal screw thread 12 in the upper, open end of the receptacle for removably securing the cap or cover thereon. The starch is preferably confined in a bag 13 of suitable cloth or material which is adapted to be placed in the container 10 with the starch therein when the cover 11 of the container 10 is removed. The bag confines the starch and affords a handy means for quickly and easily placing the starch in the container, and it also serves as a filtering medium to prevent particles of the starch from escaping into the steam or fluid passages of the pressing implement and clogging the same. When the starch container needs replenishing, the bag can be readily removed and refilled or replaced by another filled bag. Preferably, 15 the starch bag is supported in a removable metal cage or skeleton holder 14 which is adapted to be placed in and removed from the container through its open end with the bag in place in the cage. This cage facilitates the insertion and removal of the bag and also supports and holds the bag intact in the container. A screen or strainer 15 of suitable wire mesh or other straining material is also shown in the bottom of the container 10 beneath the bag and above the end of the portion B' of the supply pipe leading from the bottom of the container to the pressing implement. The strainer supplements the cloth bag in preventing particles 20 of starch from escaping from the container into the fluid supply pipe and passages in the pressing implement and clogging them. The screen or strainer 15 is preferably removable from the container so that it can be readily cleaned or replaced by a new one if necessary. As shown, this screen or strainer simply rests loosely in the lower portion of the container on an internal shoulder 16 therein, which holds the strainer 25 off of the bottom of the container.

The bag 13 is also held off of the strainer 15 by the bottom bars of the cage 14, so that in this way a free passage for the starch-laden steam or moistening fluid from the container into the pipe leading to the pressing implement is insured.

The portions B B' of the supply pipe which lead to and from the starch container preferably connect respectively with the upper and lower portions of the body thereof, as shown, so that the steam or fluid enters the upper portion of the container and discharges therefrom at the lower portion. The steam or fluid is thus caused to pass through the bag or portion of the container occupied by the starch so as to thus become impregnated or laden with starch.

A pressing iron or implement provided with my starching attachment is used in the well known manner of using pressing im-

plements provided with means for dampening the goods being pressed, and when the steam or moistening fluid is discharged from the small perforations *a* of the implement to the goods, it will moisten the goods, and at the same time, the moistening fluid being impregnated or laden with the starch, will distribute starch to the goods so as to lightly starch the same. The attachment is primarily intended for lightly starching new goods so as to improve their finish or appearance, and it has been found that goods pressed with an implement provided with my attachment are given a markedly improved appearance over goods which are moistened and pressed with similar pressing implements which are not equipped with the starching attachment. When it is desired to dampen and press the goods without starching them, the starch bag can be removed from the container 10, and the implement can then be used in the ordinary manner.

17 represents an ordinary hand valve in the supply pipe B for shutting off the steam or moistening fluid when it is not desired.

I claim as my invention:—

1. The combination with a pressing implement, of a starch container, means for passing fluid through said starch container, said pressing implement being provided with one or more perforations through which the fluid from said starch container can be delivered to the goods for dampening and starching the same while they are being pressed with the implement.

2. The combination with a pressing implement provided with one or more perforations through which fluid can be discharged to the goods while pressing the same with the implement, of a receptacle containing starch, and connections for delivering fluid through said starch receptacle to said discharge perforation or perforations of said pressing implement whereby the fluid is adapted to carry starch from said starch receptacle to the goods being pressed.

3. The combination with a pressing implement provided with one or more perforations for the discharge of fluid for dampening the goods being pressed, of a starch container in which starch is confined, pipes connected with said starch container and pressing implement arranged to cause fluid supplied to said implement for discharge through said perforation or perforations to pass through the starch in said container.

4. The combination with a pressing implement provided with one or more perforations for the discharge of fluid to the goods being pressed, of a starch container, means for delivering fluid to said container, connections through which the fluid passes from said container to said discharge perforation or perforations, said container having

a cover adapting the container to be opened, and a bag containing starch which is adapted to be inserted into and removed from said container when the latter is opened.

5. The combination with a pressing implement provided with one or more perforations for the discharge of fluid to the goods being pressed, of a starch container, means for delivering fluid to said container, connections through which the fluid passes from said container to said discharge perforation or perforations, said container having a cover adapting the container to be opened, a cage which is removable from said container, and a bag containing starch carried
- 10

by said cage and adapted to be inserted into and removed from the container while in place in said cage.

6. The combination with a pressing implement provided with one or more perforations for the discharge of fluid to the goods being pressed, of a starch container, means for delivering fluid to said container, connections through which the fluid passes from said container to said discharge perforation or perforations, a bag in said container carrying starch, a strainer between said bag and said connections, and means for holding said starch bag off of said strainer. 20
